MORRIS LOWY, OF NEW YORK, N. Y., ASSIGNOR TO LOWY PATENT FURNITURE CO. INC., OF NEW YORK, N. Y., A CORPORATION OF NEW YORK.

CRIB.

1,143,292.

Specification of Letters Patent. Patented June 15, 1915.

Application filed November 2, 1914. Serial No. 869,856.

To all whom it may concern:

Be it known that I, MORRIS LOWY, a citizen of the United States, and a resident of the city of New York, in the county of New York and State of New York, have invented certain new and useful Improvements in Cribs, of which the following is a specification.

The present invention relates to cribs, that 10 is to say to beds in which the head and foot sections are connected by side frames or side guards.

The side guards are usually slidably arranged on vertically extending guides on the 15 posts of the head and foot sections of the cribs. For holding the said side guards in their operative, that is to say in their upper positions, there are usually provided coacting means on the said side guards and the 20 posts of the head and foot sections of the crib, for instance there are hooks attached to the guides for engagement with the said guards. If a side guard is to be lowered to permit of placing a child into the crib or 25 taking the same from the crib, obviously the operator is compelled first to disengage one of the said hooks from the side guard and then to walk throughout the length of the crib for the purpose of disengaging the 30 other hook from said side guard. If she happens to have a child in her arms, considerable difficulty is experienced in disengaging the said hooks from the side guards for the reason that only one of her arms is 35 free, and the said hooks are located higher than a person of ordinary height could reach with a child in her arms.

The main object of the present invention is to provide a simple and efficient mechanism for holding a side guard of a crib in 40 its elevated operative position, said means being preferably disposed upon one of the side rails of the crib bottom and is adapted to be actuated by a pressure exerted thereon, for instance, by the leg or knee of the operator. The difficulties above mentioned are thereby effectively obviated.

With these and other objects in view, which will more fully appear as the nature 50 of the invention is better understood, the same consists in the combination, arrangement and construction of parts hereinafter fully described, pointed out in the appended claims and illustrated in the accompanying drawings, it being understood that many

changes may be made in the size and proportion of the several parts and details of construction within the scope of the appended claims without departing from the spirit or sacrificing any of the advantages of 60 the invention.

Two of the many possible embodiments of the invention are illustrated in the accompanying drawings, in which:—

Figure 1 is a side elevation of a crib embodying the features of this invention; Fig. 2 is a side elevation of a portion of one of the side guards of the crib; Fig. 3 is a section taken on line 3—3 of Fig. 2; Fig. 4 is a side elevation of a detail on an enlarged 70 scale; Fig. 5 is a plan view of the detail shown in Fig. 4; Fig. 6 is a section taken on line 6—6 of Fig. 4; Fig. 7 is a side elevation of another detail of construction; Fig. 8 is a front elevation of the detail 75 shown in Fig. 7; Fig. 9 is a side elevation of a modification of the invention; Fig. 10 is a section taken on line 10—10 of Fig. 9; and Fig. 11 is a section taken on line 11—11 of Fig. 9.

Referring more particularly to Figs. 1 to 8, inclusive, the numeral 11 indicates the head section of a crib, and the numeral 12 the foot section thereof. These sections may be made of any suitable material, for instance metal or wood, and may be of any design and shape suitable in the construction of cribs. In the drawings, the head and foot sections have been shown of a type usual in metal crib constructions, consisting 90 of posts 13, which are united at their upper ends by cross members 14, their lower ends being connected by tie-rods 15. The cross members and tie-rods are joined by bars 16 to form open-work head and foot pieces. 95 The head and foot sections of the crib are connected by side rails 17, made preferably of angle-iron, said rails supporting the crib bottom, (not shown in the drawings). Upon the posts 13 of the head and foot sections of the crib are provided vertically extending stationary guide rods 18, on which are slidably disposed the side guards 19 of the crib. Each of these side guards comprises a horizontal top bar 20 and a similarly arranged bottom bar 21, which are connected, for instance by vertical tie-bars 22. The outer tie-bars are made in the form of tubular members 23, which are slid over the guide rods 18. One of these side guards may 110

be held in operative position, that is to say in its raised position by hooks that are fastened to the guides 18 and engage the top bar 20 thereof. This construction has not 5 been shown, the same being old and well known.

The bottom bar 21 of the front side guard has attached thereto two downwardly extending lugs 24, each being provided with a 10 notch 25. In these notches are adapted to be seated projections 26 of a strip 27, the said strip abutting against the underface of the horizontal flange 28 of the side rail 17, and being slidably held thereon by guides 15 29, that are riveted or otherwise attached to the side rail. The projections 26 protrude through horizontally extending slots 30 in the vertical flange 31 of the side rail. The outer ends of these projections are bent 20 downward, as clearly shown at 32, for a purpose hereinafter to be described. To the strip 27 is attached one end of a spring 33, the other end thereof being fastened at 34 to the side rail. This spring keeps the projections 26 25 seated in the notches of the lugs 24. The strip 27 is provided with a downwardly extending operating handle 35, that is within easy reach of the leg or knee of a person.

The operation of this device is as follows: 30 In Fig. 1 of the drawings the side guard is shown in its elevated normal position, in which the projections 26 of the strip 27 are seated in the notches in the lugs 24. If it is intended to lower the side guard, it is simply necessary to shift the operating handle 35 in the direction of the arrow shown in Fig. 1 of the drawings, whereby the projections 26 become disengaged from the lugs 24 on the side guard, the latter dropping as 40 far as the guide rods will permit. The spring 33 returns the strip 27 to its normal position. The downwardly bent portions 32 of the projections 26 serve to prevent a disengagement of the lugs 24 from the said 45 projections in a lateral direction.

In Figs. 9 to 11, inclusive, a modification of the invention is shown, differing from the one above described in that, instead of the strip 27, a bar 36 is provided that abuts 50 against the vertical flange of the angle-iron of the side rail of the crib. This bar is

guided in its sliding movement by studs 37, that project through the slots 30 in the side rails and are provided with heads 38 on their free ends. The projections on the bar 36 55 are also made in the form of studs, denoted by the numeral 26', said studs having heads 39. These heads serve the same purpose as the downwardly bent portions 32 of the projections 26 described in connection with the 60 device shown in Fig. 1 of the drawings.

What I claim is:

1. A crib comprising head and foot sections, angle-iron side rails connecting the same, one of said side rails being provided with horizontally extending slots in the vertical flange thereof, a side guard slidably disposed upon said head and foot sections, a plurality of downwardly extending notched lugs upon said side guard, guides 70 upon said slotted side rail, a rigid strip upon the inner face of said slotted side rail held thereon by said guides slidable in the direction of the longitudinal axis of said side rail, and projections upon said strip 75 protruding through said slots and adapted to be seated in the notches of said lugs, substantially as and for the purpose specified.

2. A crib comprising head and foot sections, angle-iron side rails connecting the 80 same, one of said side rails being provided with horizontally extending slots in the vertical flange thereof, a side guard slidably disposed upon said head and foot sections, a plurality of downwardly extending notched 85 lugs upon said side guard, guides upon said slotted side rail, a rigid strip upon the inner face of said slotted side rail held thereon by said guides slidable in the direction of the longitudinal axis of said side rail, projections upon said strip protruding through 90 said slots and adapted to be seated in the notches of said lugs, and means for keeping said projections seated in said notches, substantially as and for the purpose specified. 95

Signed at New York, in the county of New York, and State of New York, this 30th day of October, A. D. 1914.

MORRIS LOWY.
